CLARENCE A. VAN DERVEER, OF WAKEFIELD, MASSACHUSETTS, ASSIGNEE TO HEYWOOD BROTHERS AND WAKEFIELD COMPANY, OF WAKEFIELD, MASSACHUSETTS, A CORPORATION OF NEW JERSEY.

CAR-SEAT BACK.

1,283,986.

Specification of Letters Patent. Patented Nov. 5, 1918.

Application filed December 28, 1916. Serial No. 139,375.

To all whom it may concern:

Be it known that I, CLARENCE A. VAN DERVEER, a citizen of the United States, residing at Wakefield, in the county of Middlesex and State of Massachusetts, have invented new and useful Improvements in Car-Seat Backs, of which the following is a specification.

This invention relates to railroad car seats and particularly to the means for fastening the back of the seat to the supports therefor.

Seat backs, whether upholstered or not, are made essentially of wood, and their side edges are fastened to supporting arms at the sides of the seat, by wood-screws that are screwed into the wooden frame. The use of wood-screws for this purpose has been objectionable, for the reason that the screws become loose and the screw-holes in the wooden structure have to be plugged from time to time with wooden pegs in order to make the screws hold tightly. The beneficial effect of such plugging, however, is only temporary, for the plugs themselves become worn away or split, and have to be renewed. The enlarging of the screw-holes is caused by taking out the screws to remove the back for cleaning or repairing, setting up the screws too tightly when replacing them, and, in the case of seat backs that are movable from front to back to reverse the facing direction of the seats, by sudden stopping of the back when the latter is shifted with excessive force. Too forcible shifting splits the wood in the immediate vicinity of the screws, and in some cases the splitting is so great that the placing of pegs in the screw-holes is not sufficient to repair the damage.

My present invention provides metallic anchoring means affixed permanently to the wooden structure of the back, and machine-screws for fastening the back to the side arms. The said metallic anchoring means consist preferably of metallic bars, and such bars are affixed to the side edges of the back by wood-screws. In this case the wood-screws do not need to be removed in order to permit detaching the back from the side arms that support it, and the holes into which they are screwed are not subjected to any enlarging operation after the screws have once been screwed into the wood. The machine-screws that fasten the back to the

side arms may be removed and replaced a 55 relatively great number of times without causing any enlargement of the holes in the metallic anchoring means into which they are screwed, and, furthermore, the machine-screws may be set up much more tightly 60 than wood-screws without breaking down the internal threads with which they coat.

The metallic anchoring bars are preferably mortised into the side edges of the back, the wooden structure of the back being provided with grooves for their reception; and in the case of a back that is not upholstered, the side arms that support it may cover the heads of the wood-screws and thus keep the latter from unscrewing. In 70 the case of an upholstered back, wooden fastener-receiving strips would preferably be arranged to cover the metallic anchoring bars and be nailed to the wooden frame of the back, and thus cover the heads of the 75 wood-screws and prevent the latter from unscrewing. In such case the wooden fastener-receiving strips would have holes arranged to receive the machine screws that fasten the metallic anchoring bars to the 80 side arms, and the machine-screws would pass freely through such holes in the wooden strips without depending upon the latter for anchorage. The function of the wooden fastener-receiving strips is to receive the 85 tacks or other fasteners that are used to fasten the upholstering material that is used to cover the back. When an upholstered back of such construction is fully assembled, the metallic anchoring bars and the wooden 90 fastener-receiving strips are, to all intents and purposes, integral and permanent parts thereof and do not need to be disturbed when detaching the back from the side arms.

Of the accompanying drawings:

Figure 1 represents an end elevation of a railway car seat having an upholstered back and movable side arms supporting the latter so that it may be shifted to reverse the facing direction of the seat.

Fig. 2 represents a perspective view of a portion of the wooden frame of such back.

Fig. 3 represents a front or rear elevation showing a portion of the frame of such back, a portion of one of the movable side arms 105 by which the back is supported, and a handle by which the back may be shifted and of which a passenger who is standing may take

hold. This figure shows a space between the frame of the back and the supporting arm and handle, for the reception of the upholstering material with which the back 5 would be covered.

Fig. 4 represents a cross section through the structure intersected by line 4—4 of Fig. 1.

Fig. 5 represents a cross section through 10 the structure intersected by line 5—5 of Fig. 1.

Fig. 6 represents a front elevation of a seat and back that are made without upholstering material.

15 Fig. 7 represents a cross section through the structure intersected by line 7—7 of Fig. 6.

Fig. 8 represents a cross section through 20 the structure intersected by line 8—8 of Fig. 6.

The same reference characters indicate the same parts wherever they occur.

Referring first to the structure shown by Figs. 1 to 5 inclusive,—the base of the seat is indicated as a whole at 10, and an upholstered seat-cushion is indicated at 11. Two companion side arms, such as that indicated at 12, are arranged at the sides respectively of the base 10, and in the present 30 instance are mounted upon oscillatory links 13, 13 that enable the arms 12 to be shifted to reverse the facing direction of the seat, as indicated by solid lines and by dotted lines in Fig. 1. In some cases, however, as 35 when it is not intended to reverse the facing direction of the seat, the arms 12 would be fixed.

The back is indicated as a whole at 15 in Fig. 1, and in Figs. 4 and 5 the upholstering material with which it is covered is indicated at 16. The frame of the back is made of wood, and includes two upright wooden side bars such as that indicated at 17, and top and bottom bars 18 and 19 connecting the side bars. Metallic anchoring bars 20 are affixed to the wooden bars 17 respectively, and the latter are preferably provided with grooves 21 so that the anchoring bars may be mortised into them and 50 arranged so that the outer surface of each anchoring bar will be flush with that of the wooden bar into which it is mortised. The anchoring bars are permanently fixed to the bars 17 by wood-screws 22.

55 After the metallic anchoring bars 20 have been mortised into and secured to the bars 17, wooden fastener-receiving strips 23 of substantially the same configuration as bars 17 are secured to the latter by any suitable means, such as brads 25, glue, or both. Elements 17 and 23 thus become, to all intents and purposes, an integral wooden structure to which the upholstering material 60 16 may be fastened just as though the metallic anchoring bars were omitted. When

the wooden strips 23 are used they cover the heads of the wood-screws 22, and the latter are thus positively held against unscrewing. It is therefore impossible for the metallic bars 20 to become loosened relatively to the 70 frame of the back.

As shown by Figs. 4, and 5, the marginal portions of sheet material 16 are lapped upon and secured to the fastener-receiving strips 23, tacks 24 being driven through the 75 upholstering material and into the wooden strips for this purpose.

The back is supported by the metallic anchoring bars 20, and is detachably connected to the arms 12 by machine-screws 26 the 80 screw-threads 27 of which coat with corresponding internal screw-threads tapped in the said bars. See Figs. 3 and 5. Incidentally to this connection the screws 26 pass through holes formed in the wooden strips 85 23, said holes being large enough to enable the screws to pass freely through them. The wooden bars 17 of the back frame are preferably bored as indicated at 28, to provide clearance for the inner ends of the 90 anchoring screws 26. The anchorage for the screws 26 is therefore exclusively in the metallic bars 20, and the screws may be set up as tightly as desired without breaking down the internal screw-threads that hold 95 them.

The thickness of the lower frame-bar 19 is substantially the same as the width of the metallic anchoring bars 20, and the lower portions of the members 17 and 23 are tapered to the same width, in consequence of which formation the back 15 conforms approximately to the back of the occupant of the seat. This reduction in thickness at the lower part of the back is desirable both for 100 the comfort of the occupant and because it saves an appreciable amount of space in the car. The seats may be arranged approximately two inches nearer each other (from center to center) than they could be with 105 backs that have the usual thickness at the bottom, and still leave as much space between the seats as formerly. In the present instance the reduction in thickness at the lower part of the back does not weaken the 110 back, because the metallic anchoring bars 20 reinforce the wooden structure of the back, and the shocks and stresses incidental to shifting the back and to leaning against it are sustained by said bars.

120 Figs. 6, 7 and 8 illustrate a non-upholstered back, the wooden frame-members 17' of which correspond to the members 17 hereinbefore described. Grooves 21' are formed in the side edges of the members 17', and 125 metallic anchoring bars 20' are arranged in said grooves and are fixed to the members 17' by wood-screws 22'. Inasmuch as no upholstering material is used for a back of this type, there is no necessity for placing 130

wooden strips, such as those indicated at 28, over the metallic anchoring bars, and consequently the side arms 12 may lie in contact with the bars 20', and are so shown. The 5 bars 20' and arms 12 are connected by machine-screws 26', the screw-threads 27' of which coat with internal screw-threads tapped in the bars 20'. In this modification the arms 12 cover the heads of the wood- 10 screws 22' and prevent the latter from unscrewing.

In each of the modifications a handle 30 is affixed to one upper corner of the back, to afford means of which passengers may take 15 hold, and, if the back is of the reversible type, to afford means whereby the back may be conveniently shifted. The handle is provided with an anchoring portion 31 that is arranged against one side edge of the back. 20 When the back is to be provided with a handle I provide anchoring bars 20 of sufficient length to receive the anchoring screws 32 by which the portion 31 of the handle is anchored. Screws 32 are machine-screws 25 similar to those indicated at 26 and 26', and the metallic anchoring bar is bored and tapped with internal screw-threads to coat with the threads of the screws 32. Thus the handle 30 may be anchored directly to 30 the metallic bar, which in turn is anchored directly to one of the arms 12. In the present instance the handle 30 has another anchoring portion 33, and the latter is arranged upon the upper edge of the back and 35 is anchored to the upper bar 18 by a wood-screw 34. The screws 32, however, sustain the greater part of the stresses to which the handle is subjected, and in view of the relatively strong anchorage afforded by them 40 the single wood-screw 34 is sufficient as an auxiliary anchorage.

I claim:

1. A car seat comprising an upholstered back including a wooden frame and a covering of sheet material, metallic anchoring bars fastened to said frame and arranged to extend along the side edges thereof inside said covering of sheet material, side arms arranged to support said back by said bars, 50 and means arranged to affix said bars to said arms.

2. A car seat having a back including a wooden frame and upholstering material, metallic bars arranged to extend along the 55 side edges of said frame, wood-screws arranged to fasten said bars to said frame, wooden strips arranged against the outer

sides of said bars and covering the heads of said wood-screws, said wooden strips being fastened to said frame, said upholstering material being arranged against the outer side of said wooden strips, fasteners arranged to fasten said upholstering material to said wooden strips, side arms arranged to support said back by said metallic bars, and 60 anchoring screws arranged to fasten said bars to said arms, said anchoring screws extending through said wooden strips and into said bars, said anchoring screws and said bars having coactive screw-threads. 70

3. A car seat having a back including upholstering material, side arms arranged to support said back, and anchoring screws connecting said back rigidly to said side arms, said back comprising a frame including upright wooden side bars, metallic anchoring bars embedded in and affixed to said wooden bars respectively, said wooden bars being rabbeted for the reception of said anchoring bars, and wooden fastener-receiving 80 members affixed to said wooden side bars and arranged to extend between said arms and anchoring bars respectively, said screws extending through said fastener-receiving members, said anchoring bars and said 85 screws having coactive screw-threads, said upholstering material being secured to said wooden fastener-receiving members.

4. A car seat comprising an upholstered 90 back including a wooden frame and a covering of sheet material, side arms arranged to support said back, screws extending through said arms and into said frame, and metallic anchoring members inside said covering and having internal screw-threads 95 to coat with said screws, said anchoring members being arranged to coat with said screws to fix said back to said arms.

5. A car seat comprising an upholstered 100 back including a wooden frame and a covering of sheet material, metallic anchoring bars arranged to extend along the side edges of said frame inside said covering, means arranged to fasten said bars to said frame, wooden strips arranged between said bars 105 and said covering, said covering being fastened to said strips, side arms arranged to support said back by said bars, and screws arranged to coat with said arms and bars to fix said back to said arms. 110

In testimony whereof I have affixed my signature.

CLARENCE A. VAN DERVEER.
